RADIO TRANSMITTING SYSTEM

Edwin H. Armstrong, New York, N. Y.

Application August 25, 1936, Serial No. 97,736

2 Claims. (Cl. 179—171)

This invention relates to an improvement in the method of modulating the transmitter described in my U. S. Patent #1,941,068, whereby a more symmetrical frequency characteristic is obtained and whereby distortion in the radiated wave is reduced.

The invention is of particular importance where a wide range of modulating frequencies are employed such as in multiplex signaling, television and the like, because it is difficult with the arrangement shown in the said patent to prevent asymmetrical phase shift at the higher frequencies of modulation.

Fig. I illustrates the arrangement for carrying out the invention. In this figure, 1 represents the master oscillator, 2 a buffer amplifier and 3 a transformer. In the secondary of this transformer are three parallel circuits, one containing the resistances 6 and 7 in series with each other, the other two containing respectively resistance, capacity, and inductance in series as shown. 12 is an amplifier whose grid is excited by the voltage developed across the resistance 7. 14 and 15 are likewise amplifiers whose grids are excited respectively by the voltages existing across the capacity 9 and the inductance 11. The plates of the tubes 14, 15 are connected in parallel with each other and arranged to have a common plate load with the tube 12 by means of the resistance 13. 16 represents an amplifier of the combined outputs of the tubes 12, 14 and 15. 17 is a band pass filter for eliminating undesired harmonics, 18 is a frequency multiplier and 18a represents the output of the system. 19 represents the input of the modulating system, 20 an amplifier, 21 a blocking condenser, 22, 23 the correction system, and 24 an amplifier which differentially modulates the screen grids of the amplifiers 14 and 15 thru the transformer 25.

The method of operation of the system is as follows. The master oscillator 1 produces in the output circuit of the transformer 3 a current of the desired frequency. This current is split up into three parts; one to each branch of the parallel system. The inductance and capacity combinations in the two branches containing reactance are made non-reactive for the oscillator frequency. The currents in the three branch circuits are therefore all in phase with each other. The E. M. F. developed across the resistance 7 which is applied to the grid of the amplifier 12 is, consequently, in phase with this current. The E. M. F. developed across condenser 9 which is applied to the grid of the modulator 15 is 90° ahead of the current and the E. M. F. developed

across the inductance 11 which is applied to the grid of the modulator 14 is 90° behind the current. These two E. M. F.'s electromotive forces differ from each other by 180°. By making the resistances 4 and 5 equal to each other and the reactances of condenser 9 and inductance 11 likewise equal to each other for the oscillator frequency the voltages applied to the grids of 14 and 15 may be made equal in amplitude and opposite in phase. Since the electromotive forces applied to the grids of the tubes 14 and 15 are equal in magnitude and opposite in phase it follows that the currents in the plate circuits of these tubes are equal and opposite in phase. Consequently in the absence of modulation the only current which 15 flows thru the resistance 13 which is common to the three tubes 12, 14 and 15 will be the current due to the amplifier 12. This current will be in phase with the E. M. F. applied to the grid of the tube.

Suppose now that the potential of the screen grids of the modulator tubes 14 and 15 be changed, one being made more positive and the other being made more negative. More current will flow thru the tube whose screen grid potential has been rendered more positive and less current will flow thru the tube whose screen grid potential has been rendered less positive. Consequently the two currents no longer balance each other and the difference will flow thru the resistance 13. Since 30 the E. M. F.'s applied to the grids of the modulator tubes 14 and 15 are respectively each 90° removed in phase from the voltage applied to the grid of the tube 12, the resultant plate current or current flowing thru the resistance 13 due to the difference in the currents thru the tubes 14 and 15 will be 90° different in phase from the current produced therein by the tube 12. The resultant plate current flowing thru the resistance 13 will either lead or lag the current therein due to the tube 12, 40 depending on the instantaneous polarity of the modulation applied to the screen grids of the tubes 14 and 15. Hence the voltage developed across the resistance 13 which is the vector sum of the voltages produced by the current due to the 45 tube 12 and the resultant current of the two modulator tubes 14 and 15 will be alternately advanced and retarded in phase with respect to the phase of the voltage of the master oscillator.

The angle of the phase shift will be, within 50 limits of the order of 30°, directly proportional to the amplitude of the resultant current from the modulator tubes 14 and 15. By making the amplitude of this current inversely proportional to the frequency of the modulating current by 55

means of the correction systems 22, 23 and multiplying the frequency a sufficient number of times by multiplier 18 as described in my U. S. Patent #1,941,068 there will be produced a frequency 5 modulated wave in the manner described in the aforementioned patent, but having the advantage of a uniform frequency characteristic and freedom from certain distortions which may be present in the system described in that patent. In 10 the present system, it is unnecessary to introduce any phase-changing network in the output circuits of the modulator tubes. The output of the modulator tubes may be combined directly with the output of the carrier amplifier tube in a common 15 aperiodic load. This removes the limitation which the phase-shifting network in the output of the modulator tubes of the old system may impose upon a uniform frequency characteristic.

I have described what I believe to be the best 20 embodiment of my invention. I do not wish, however, to be confined to the embodiment shown, but what I desire to cover by Letters Patent is set forth in the appended claims.

I claim:

25 1. Apparatus for modulating the phase of a

radio frequency carrier, comprising means for generating a radio frequency carrier current of fixed frequency, an amplifier, a balanced modulator, means for applying the radio frequency carrier current to the input circuit of said amplifier and said balanced modulator in such phase relation that the voltages applied to the inputs of the modulators are 180° out of phase with each other, and 90° out of phase with the current applied to the input of the amplifier, and means for combining 10 the output of the amplifier and modulator.

2. Apparatus for modulating the phase of a radio frequency carrier, comprising means for generating a radio frequency carrier current of fixed frequency, an amplifier, a balanced modulator, means for applying the radio frequency carrier current to the input circuit of said amplifier and said balanced modulator in such phase relation that the voltages applied to the inputs of the modulators are 180° out of phase with each other, 15 and 90° out of phase with the current applied to the input of the amplifier, and an aperiodic load for combining the output of the amplifier and modulator.
